UNITED STATES PATENT OFFICE.

LEO GILLIG AND CHESTER GILLIG, OF SAN FRANCISCO, CALIFORNIA.

DESIGN FOR AN AUTOMOBILE-TOP.

57,635.

Specification for Design. Patented Apr. 26, 1921.

Application filed October 8, 1919. Serial No. 329,372. Term of patent 7 years.

To all whom it may concern:

Be it known that we, LEO GILLIG and CHESTER GILLIG, citizens of the United States, and residents of the city and county of San Francisco and State of California, have invented a new, original, and ornamental Design for an Automobile-Top, of which the following is a specification, reference being had to the accompanying drawing, forming a part thereof.

In the drawing:

Figure 1 is a side elevation of the top,

Fig. 2 is a front elevation,

Fig. 3 is an end elevation looking from the rear.

Fig. 4 is a plan view of the top.

What we claim is:—

The new and ornamental design for an automobile top substantially as shown.

In testimony whereof we have hereunto set our hands this 30th day of September, 1919, in the presence of the two subscribed witnesses.

LEO GILLIG.
CHESTER GILLIG.
